UNITED STATES PATENT OFFICE.

ADOLPH BLOME, OF HOBOKEN, NEW JERSEY, ASSIGNOR, BY DIRECT AND MESNE ASSIGNMENTS, TO IDA BLOME, OF SAME PLACE.

SCRAP-BOOK.

SPECIFICATION forming part of Letters Patent No. 537,599, dated April 16, 1895.

Application filed May 16, 1893. Serial No. 474,216. (No model.)

To all whom it may concern:

Be it known that I, ADOLPH BLOME, of the city of Hoboken, in the county of Hudson and State of New Jersey, have invented certain 5 new and useful Improvements in Scrap-Books, of which the following is a specification.

The object of my invention is to produce a scrap-book which shall be durable, cheap and easy to manufacture, and adapted to contain 10 a greater number or quantity of scraps such as in invoices, prescriptions, letters, newspaper clippings, &c., within each section of the several sections or signatures of which the book is constructed, than any scrap-book heretofore 15 made and used; and my invention also relates to a novel method of manufacturing the guard or back-piece.

In the accompanying drawings, forming a part hereof, Figure 1 represents a machine or 20 device by means of which or on which the guard or back-piece is constructed. Fig. 2 is a perspective view of a guard or back-piece constructed according to my invention. Fig 3 is a perspective view partly broken away of one 25 of the interposed strips or bars; and Fig. 4 is a perspective view of a scrap-book constructed according to and embodying my invention.

A is a base-plate of metal or other suitable material from which rise any number of up- 30 rights or standards B, which uprights or standards may be cast with the base-plate A or made separately, and afterward securely fastened thereto; and these standards may be of any desired size,—length, height and thick- 35 ness, and arranged on the plate A at any de- sired distance apart according to the character and size of the book to which the guard is in- tended to be attached, or of which the guard is to form a part, and any number of stand- 40 ards may be used. This device or die may be located in any desired place, and may be se- cured to a platform, table or the like on which it rests by means of the screws C, which pass through openings in the extending ends of 45 the base-plate A, as shown in Fig. 1.

I make the guard or back-piece shown in Fig. 2 with or on the device shown in Fig. 1 as follows:—On the top of the standards B, I lay a piece, strip or sheet D of paper, linen, 50 muslin or other fibrous, textile or suitable

material and apply to the upper surface of such sheet a layer or coating of glue, paste, cement or other adhesive material and commencing at one end of the plate A or at the uprights at one end of the plate A, I press the superimposed strip or sheet D into the spaces or grooves E between the several uprights B in succession by means of separate pieces, strips or bars F, as shown in Fig. 3, of any suitable material, as paste-board, wood or other material and which pieces, strips or bars are made of substantially such size as will fit the spaces or grooves between the uprights B and continuing the operation until all of the spaces between the uprights B are filled, I thereby force the superimposed strip D between the several uprights by as many separate bars or strips F as there may be spaces, whereby the spaces between the uprights will be filled with the bars F and the surrounding strip D, to which strip D the bars will adhere and become fastened or attached or stuck by means of the glue, paste or other adhesive substance that has been applied to the strip as before stated; and after allowing said strip with the surrounding sheet D to remain in the machine or die shown in Fig. 1 for a sufficient length of time for the glue or other adhesive material to harden or set, I lift the whole structure which is then in the die, comprising the sheet D and the strips F, from or out of the die of which it will form a counterpart, and it will then be of the character shown in Fig. 2, consisting of alternate tongues T and grooves S, comprising the guard or back-piece of the book; or the sheet may first be folded on the die shown and described or in any other manner, and the bars F afterward inserted in the folds of the folded sheet and secured therein by glue or other adhesive substance that may have been applied thereto, producing a guard like that shown in Fig. 2, to which the signatures may be united.

While I have used the word "sheet" D as referring to a single sheet of material, it is to be understood that any number of such sheets may be secured together by suitable adhesive substance forming several plies or thicknesses which may be laid across the tops of the stand- 100

ards B and adhesive substance applied to the upper surface thereof, and the bars F pressed down between the several uprights in the manner just above explained, and in Fig. 2 I have illustrated a guard or back-piece constructed according to my invention and made on the device shown in Fig. 1, using two sheets, one of paper D upon which has been applied a sheet or strip of crash G, and I preferably 10 use crash in conjunction with paper or other fibrous, textile or woven material, since the same application of adhesive substance which will secure the crash to the sheet D will leave sufficient quantity protruding through the 15 meshes of the crash to securely unite or fasten the bars F thereto, the sheets D and G being placed on the tops of the standards B and the strips F pressed into the spaces between the uprights B, at the same time press- 20 ing the combined sheets D and G between the spaces as will be readily understood.

Thus I am enabled to produce a very strong guard or back-piece, which is very quickly, 25 easily and cheaply manufactured considering the element of time employed within which to construct it. This guard can then be attached to the several sections or signatures in any convenient manner, as by sewing the 30 several sections or signatures H to the sheet D or combined sheets at the places or portions thereof designated at I in Fig. 2, which are located between the several enveloped bars F or tongues T as will be readily understood from that figure, the sections being inserted 35 between the tongues T or enveloped bars F, the thread passing through the fold of the folded leaves comprising the signatures and through the sheet D or sheets D and G at the portions I of the guard, in the usual manner; 40 and the extending ends of the guard may then be securely attached to the covers K of the book in any convenient manner, and the covers then wrapped with paper, leather, cloth and the like as desired, the extending edges 45 being fastened either on the outside or inside of each cover-board, or between the cover-boards where two boards are used for each cover, as shown in Fig. 4.

Thus by my invention I am enabled to produce 50 a book of any desired thickness, since according to the thickness desired I use a die, having any number of standards, or for a small book I can employ a portion of the standards, leaving the others for use with a larger book, 55 as will be readily understood. Then again I am enabled to produce a book having a guard or back-piece of any desired depth, according to the purpose desired, and to construct which I use a die in which the standards shall be 60 of the proper desired height, and of course the bars F will in that event be made of a corresponding height; and again I am enabled to produce a book whereby the space between the several sections or signatures at the back 65 of the book may be of any desired extent or width according as the space between the uprights B, and according as to which space be-

tween the uprights B will be the thickness of the bars F which are to be pressed therein as before explained; and all of which advantages 70 of depth of back-piece or guard and space between the sections and corresponding thickness of bars F can be attained in one book and the features of being enabled to make the guard of any desired depth and the space 75 between the sections of any desired amount are very desirable and of great advantage in a scrap-book, since a greater number of loose scraps, as invoices, checks, prescriptions, clippings, &c., may be secured or stuck to each 80 leaf of the several sections or signatures, and the thickness of the book with the scraps applied, will not be greater at the front than the thickness of the book at the back, as is very frequently the case with scrap-books; 85 and again, where the guard is made deep, as shown in Fig. 4, the several sections with the scraps attached to the leaves, making the several leaves heavy, will not become as readily detached from the guard as there is greater 90 flexibility in the handling of the book and the turning of the separate sections or leaves, and whereby the guard will not be as liable to become broken, as also not infrequently happens.

For convenience of the sewers the guard 95 may be constructed in sections, the ends of the several sections being united together forming when united one continuous guard like that shown in Fig. 2.

I do not limit my invention to any particular size or character of book, nor to the purpose for which said book may be used; nor do I limit my invention to any particular character of materials of which the guard may be 105 constructed nor to the precise order of operations in carrying out my improved method or process, nor to the precise detail of the operations hereinbefore described, but

What I claim as my invention, and desire 110 to secure by Letters Patent, is—

1. As an improved product the herein described guard or back-piece for books consisting of a sheet formed in reverse folds, and narrow and deep bars or strips F in the alternate folds thereof arranged with their wide faces facing each other, said sheet being tightly and smoothly secured by adhesive material upon said bars or strips F on the opposite side faces of said bars and on one edge of each of said bars and one series of folds of the said folded strip containing said bars and the other adapted to contain the signatures, substantially as set forth.

2. The method of manufacturing a guard 115 or back piece for books which consists in pressing a sheet of suitable material into the grooves or spaces between the uprights or standards of a die by separate bars which are adapted to fit into said grooves so as to produce a folded sheet the counterpart of the die, and causing said bars to adhere to said sheet, 120 substantially as set forth.

3. The method of manufacturing a guard

- or back-piece for books which consists in applying adhesive substance to the surface of a sheet of material and pressing said material into the grooves or spaces between the uprights or standards of a die by separate bars which are adapted to fit into said grooves or spaces so as to produce a guard or back-piece out of said strip conformed into alternate tongues and grooves, the counterpart of the die, the tongues being created by the bars which have been used to press the strip into the grooves in the die, and which bars are securely held in the folds or grooves of said sheet by means of the adhesive substance 15 that has been applied thereto, substantially as set forth.
4. The method of manufacturing a book which consists in producing a guard or back-piece consisting of alternate tongues and 20 grooves by pressing a sheet of material into the grooves or spaces between the uprights or standards of a die by means of separate bars which are adapted to fit into said grooves or spaces in said die over or onto said sheet, 25 and uniting the bars and sheet and then re-
- moving the guard so made from the die of which die the guard will be the counterpart and then securely uniting the several sections or signatures of the book to the several portions of the folded sheet located between the 30 tongues, and then attaching the unfolded ends of the sheet to the covers of the book, substantially as set forth.
5. The method of manufacturing a guard or back piece for books which consists in 35 pressing a sheet of suitable material into the grooves or spaces between the uprights or standards of a die so as to produce a folded sheet the counterpart of said dye, and securing within the said grooves or spaces formed 40 in the sheet between the uprights of the die, by adhesive material, separate bars adapted to fit therein, substantially as set forth.

This specification signed and witnessed this 12th day of May, A. D. 1893.

ADOLPH BLOME.
